CLAIM

The ornamental design for a tablet case, as shown and described.

DESCRIPTION

FIG. 1 is a front, right, and top perspective view of a tablet case, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right, and top perspective view of a tablet case of FIG. 1, where in the lid of the tablet case is closed. FIG. 10 is a front, right, and top perspective view of a tablet case of FIG. 1, where in the lid of the tablet case is folded up.

FIG. 11 is a partial enlarged view of an area labeled 11 in FIG. 1 comprising a lens hole; and,

FIG. 12 is a partial enlarged view of an area labeled 12 in FIG. 1 comprising the part between the cover and the protective shell.

The broken lines depict portions of the structure that forms no part of the claim. The dot-dash-dot lines marking the enlargements form no part of the claim.
